US0D1110697S

(12) United States Design Patent (10) Patent No.: US D1,110,697 S
(45) Date of Patent:  Feb. 3, 2026

(54) SHOE

(71) Applicant: Converse Inc., Boston, MA (US)
(72) Inventor: John Heinrich, Boston, MA (US)
(73) Assignee: Converse Inc., Boston, MA (US)
() Term: 15 Years
(21) Appl. No.: 29/956,213
(22) Filed: Aug. 6, 2024
(51) LOC (15) Cl. 02-04
(52) U.S. Cl.
USPC D2/947; D2/960

(58) Field of Classification Search

USPC ..... D2/896, 902, 903, 905–909, 916, 919, D2/923, 947, 951–960, 946, 972, 977; 36/3 B, 22 R, 24.5, 25 R, 28, 32 R, 34 R, 36/59 C, 67 A, 103, 114

CLAIM

The ornamental design for a shoe as shown and described.

DESCRIPTION

FIG. 1 is a side view of a shoe showing my new design; FIG. 2 is a rear perspective view thereof; FIG. 3 is a rear view thereof; FIG. 4 is an opposite side rear perspective view thereof; and, FIG. 5 is an opposite side view thereof. The broken lines depicting the remainder of the shoe form no part of the claimed design.

1 Claim, 5 Drawing Sheets
